FIG. 1

FIG. 2

FIG. 3

FIGURE 1 is a view of the waffle grill showing my new design, it being understood that the quarter-section design of the grip shown in full lines in the upper part of the grill is repeated throughout the remaining three quarter-sections, which have been omitted for convenience of illustration;

FIGURE 2 is a view of the grill showing a quarter-section design of the grid in full lines in the lower part of the grill and it being understood that the grid design is repeated throughout the remaining three quarter-sections; and

FIGURE 3 is a cross-sectional view taken through the line 3—3 of FIGURE 2.

The dominant features of my design are shown in full lines.

The top and bottom surfaces of the grill not illustrated are substantially plain.

The bottom surface of the grid not illustrated is substantially plain.

This is a division of design patent application Serial No. D-70,666 filed June 25, 1962.

I claim:

The ornamental design for a waffle grill, substantially as shown and described.
